HEADER FOR FURNITURE

Richard M. Chapin, Charlotte, N.C., assignor to Dolly Madison Industries, Huntingburg, Ind.

Filed Jan. 7, 1972, Ser. No. 216,333

Term of patent 7 years

Int. Cl. D6—06

U.S. Cl. D6—192

FIG. 1

FIG. 3

FIG. 1 is a front elevational view of header for furniture showing my new design;

FIG. 2 is an enlarged cross-sectional view taken substantially along line 2—2 in FIG. 1; and

FIG. 3 is an enlarged cross-sectional view taken substantially along line 3—3 in FIG. 1.

I claim:

The ornamental design for a header for furniture, substantially as shown and described.
